(57) **CLAIM**

The ornamental design for a wall mount power supply, as shown and described.

DESCRIPTION

FIG. 1 is a top, rear, left isometric view of a wall mount power supply showing our new design;

FIG. 2 is a top plan view thereof;

FIG. 3 is a front elevated view thereof;

FIG. 4 is a rear elevated view thereof;

FIG. 5 is a right side elevated view thereof, the left side being a mirror image thereof; and,

FIG. 6 is a bottom plan view thereof.
